DESIGN FOR A MULTIPLE ENVELOPE OR SIMILAR PACKAGE

Leroy L. Salfisberg, South Orange, N. J., assignor
to Ivers-Lee Company, Newark, N. J., a corpora-
tion of Delaware

Application February 4, 1942, Serial No. 105,626

Term of patent 14 years

To all whom it may concern:

Be it known that I, Leroy L. Salfisberg, a citizen of the United States and a resident of South Orange, in the county of Essex and State of New Jersey, have invented a new, original, and ornamental Design for a Multiple Envelope or Similar Package, of which the following is a specification, reference being had to the accompanying drawing, forming part thereof.

Figure 1 is a front elevational view of a multiple envelope or similar package showing my new design.

Figure 2 is an elevational view of one edge of the multiple envelope or similar package shown in Figure 1.

Figure 3 is a fragmentary front elevational view on an enlarged scale of a portion of the multiple envelope or similar package along the line 3—3 of Figure 1.

Figure 4 is a fragmentary vertical longitudi-

nal sectional view on the line 4—4 of Figure 3, and

Figure 5 is a transverse sectional view on the line 5—5 of Figure 3.

The dominant features of my design reside in a multiple envelope of the configuration disclosed having compartments of the specific contour shown defined by crimped areas comprising rows of alternate substantially square projections and substantially concavely curved surfaces of octagonal outline alternating with rows of substantially square indentations and substantially convexly curved surfaces of octagonal outline forming borders disposed in the specific manner illustrated.

I claim:

The ornamental design for a multiple envelope or similar package, as shown and described.

LEROY L. SALFISBERG.
